FLASHER

Edwin H. Pendleton, Venice, Calif., assignor to
Econolite Corporation, Los Angeles, Calif., a
corporation of California

Application April 10, 1933, Serial No. 665,311

2 Claims. (200—19)

My invention relates to means for giving an interrupted electric current and is especially related to a device utilizing an interrupted electric current for indicating and illuminating purposes.

5 An object of my invention is to provide means for operating an indicator such as a gaseous discharge tube preferably of the neon type, with a very small amount of electric current.

10 Another object of my invention is to provide means for giving an interrupted or repetitive flash to a tube such as a neon tube, over a long period of time without attention to the apparatus.

15 A further object of my invention is to provide an electric current interrupter in which interrupting contacts are utilized in a fashion to inhibit deleterious contact conditions.

20 The foregoing and other objects are attained in the embodiment of the invention shown in the drawings, in which—

Figure 1 is a plan of a flasher constructed in accordance with my invention.

25 Figure 2 is a side elevation of the flasher shown in Figure 1, a portion being broken away to disclose the interior construction.

Figure 3 is a cross-section the plane of which is indicated by the line 3—3 of Figure 1.

Figure 4 is a cross-section the plane of which is indicated by the line 4—4 of Figure 2.

30 Figure 5 is a front elevation of a sign incorporating the flasher of my invention therein.

Figure 6 is a diagram of a circuit useful in conjunction with the flasher of my invention.

35 In its preferred form, my flasher includes a timing device which is effective to drive a periodically vibrating contact arm which in turn controls an electric circuit including an indicator such as a gaseous discharge or neon tube, for providing a repetitive series of flashes in the tube.

40 In the preferred form of my invention I preferably provide a flashing unit, generally designated 6, which incorporates a housing 7 having a cover plate 8. Within the housing is situated a spindle 9 which at its upper end is contoured

45 to seat a ball 11 on which rests a pivot block 12. The pivot block is joined by a metal tube 13 surrounding the spindle 11, to a relatively massive metallic disc 14 in effect forming a momentum device or fly wheel. Due to the single pivot bearing, the fly wheel turns with a minimum of friction.

50 In order to constrain the fly wheel toward one extreme position, I preferably encompass the sleeve 13 with a spiral spring 16 having one end

anchored on the sleeve 13 and the other end fastened to the casing 7 by a conducting arm 17. The described conducting parts provide a circuit from the arm 17 through the spring 16 and the sleeve 13 to the disc 14. Mounted on the disc is an abutment 18 which, during oscillatory movement of the disc 14, describes a path into which projects an extension 19 of an armature 21. At its upper end the armature is provided with a pair of ears 22 carrying an axle 23 mounted in an eared bracket 24 fastened to a support 26 on the cover plate 8. Situated on the member 26 is an electromagnet 27 having a core 28 in magnetic juxtaposition with the armature 21. A leaf spring 29 on the armature assists the spring 16 in maintaining the armature away from the core 28, but when the core is energized the armature is attracted thereto and imparts an impulse to the disc 14, causing an oscillation thereof, against the urgency of the spring 16. When, however, the core 28 is de-energized the springs 29 and 16 are effective to return the armature to its original spaced position and against a bumper spring 31 mounted on a bracket 32 on the cover plate 8.

Since, as shown in Figure 6, the circuit for the electromagnet 27 preferably includes a lead 33 extending from a source of electromotive force, such as a battery 34, to the electromagnet, and is completed through a master switch 36 and a lead 38 to the disc 14 and through the abutment 18 and the armature 19 to the coil, when the armature is in contact with the abutment the circuit is completed, providing the master switch is also closed. This mechanism is therefore effective to give a succession of impulses to the oscillating disc 14 at equally spaced intervals, so that the mechanism is in effect a timing mechanism with the disc making oscillations within predetermined timed periods and with considerable accuracy.

55 In accordance with my invention, I make use of the regulated impulses from the driving or timing mechanism, to affect a contact arm having a natural period of vibration. To this end there is mounted on the cover plate 8 a support 41 to which is secured one end of a relatively long leaf-spring 42, preferably constructed of phosphor-bronze or comparable material. The contact arm 42 at its opposite end is provided with a contact 43 and can also be provided with a weight 44 to establish at a desired value the natural period of vibration of the contact arm with respect to its base 41. The contact arm is restrained in its amplitude of movement by an upper stop 46 which constitutes a bracket secured to the cover plate 8, and by a lower stop 47 which constitutes

an adjustable screw mounted in the cover plate 8.

In order that driving movement from the timing unit may be imparted to the contact arm 42, I preferably dispose on the sleeve 13 a cylindrical face cam 48 the lower periphery of which is suitably contoured to contact one arm 49 of a crank 51 journaled in a bearing block 52 mounted on the cover plate 8. The other end 53 of the crank is situated below the vibratile contact arm 10 42, and, in the at-rest position of the apparatus, or in the position at the end of a cycle, bows or 15 stresses the contact arm 42 from its natural position and against the upper stop 46. When, during the rotation of the disc 14, the cam releases 15 the arm 49, the arm 53 no longer abuts the contact arm 42, and in resuming its normal shape from a stressed condition the contact arm 42 is set into vibration with a natural frequency.

In order to vary the period of vibration of the 20 contact arm, I preferably mount an adjustment, generally designated 56, on the cover plate. This adjustment comprises a crank 57 carrying a cam surface 58 adapted to abut the underside of the contact arm 42. The crank 57 is rotatable in a 25 supporting block 59 secured to the cover plate. By rotating the crank 57 to any selected position, the fulcrum of the contact arm 42 is varied within a reasonable range to alter the vibration period.

The movements of the contact arm are utilized 30 to control an electrical circuit, and to this end I preferably place in association with the contact 43 a second contact 61 which is mounted adjacent one end of a second contact arm 62, at its other end anchored as at 63 to the cover plate 8. 35 The second contact arm 62 has its own natural frequency of vibration which, due to the smaller size of the arm and its different mounting, is preferably a faster frequency than that of the arm 42; so that for each vibration of the arm 42 40 several vibrations of the contact arm 62 occur. Thus, when the contact arm 42 is strained, as shown in Figure 2, and subsequently released, it makes several complete oscillations, at the end of each striking the contact 61 and setting the 45 contact arm 62 into vibration at a much faster rate, so that in effect a plurality of abutments occur between the contacts 43 and 61 for each operation of the crank 53. The adjusting screw 47 is important in changing the amplitude of 50 vibration of the contact arm 42 to affect the number and duration of contacts between the points 43 and 61.

The contacts 43 and 61 control the primary winding 66 of a transformer 67, so that for each 55 operation of the crank arm 53 the primary coil 66 of the transformer is energized and de-energized a plurality of times. This energization is effective correspondingly to energize the secondary 68 of the transformer, which is connected 60 in an electrical circuit with an indicator such as a gaseous discharge tube 69, preferably of the neon type; and therefore a plurality of very short but rapidly successive flashes is produced in the tube 69 for each oscillation of the disc 14. Preferably, the flashes in the tube 69 are of such frequency and duration that, due to persistence of vision, a sequence of apparently continuous flashes spaced at short times apart appears to an observer.

The arrangement is such that the primary contact arm 42 may make five or six relatively long- 70 appearing flashes for each oscillation of the disc 14, and during each of the four or five apparently long flashes the secondary contact arm 62 provides several interruptions, so that, although each

flash may in itself appear to be complete, it is in fact in turn rapidly interrupted in order to save as much electrical current as possible. The strain on the battery 34 is reduced to such an extent that an ordinary neon tube 69 can be 5 supplied with current from a standard battery to flash for a period of from six months to a year without renewal and without attention. The relatively long life of battery insured by the extremely small consumption of current makes it 10 possible to install the flasher of my invention in a sign 71, for instance, which includes a standard 15 72 on which is mounted a casing 73, hollow in its interior to contain the battery 34 and the flasher unit, and on its face carrying a neon tube 69 bent 15 to form an indicium.

Since this mechanism is designed for extremely long operation without attention, it is important that the contacts 43 and 61 be held apart 20 in the event of failure of the mechanism or in the event of pitting of the contacts which might normally tend to leave the circuit closed and cause a severe drain on the battery. To this end I provide means for positively separating the contacts in the event the current passing through 25 them should for any reason become excessive.

As particularly indicated in Figures 2 and 6, I mount an electromagnet 74 within the housing 7 and arrange the electromagnet with its core 16 immediately below the contact 61. The electromagnet is preferably connected in circuit from the battery 34 by a lead 77 which extends to a contact 78. Co-operative with the contact 78 and normally in abutment therewith, is a contact 79 joined to a lead 81 extending to the electromagnetic coil 74 and from thence to the contact 61. In the event of only normal current flow, the electromagnet 74 is not sufficiently energized to have any effect, appreciably, upon the contact 61, but in the event of excessive current flow the pull of the electromagnet 74 is sufficient to separate the contact 61 if it should be stuck to the contact 43 and to pull the contact arm 62 sufficiently toward the core 16 so that the contact arm 62 touches the contact 79 and pulls it away 45 from the contact 78, thereby positively breaking the circuit. In the event the contacts 43 and 61 do not further stick, the mechanism returns to its normal operation; but in the event the sticking continues, a successive break is made in order 50 to prevent major drain on the battery 34. As a further precaution to preclude burning or arcing of the contacts 43 and 61, a condenser 82 is preferably connected in parallel with the contacts 43 and 61.

As a further precaution to inhibit severe alteration of the contact faces, I preferably include in the circuit a pair of contacts 83 and 84 which are carried by supporting arms 86 and 87 mounted on the cover plate 8 and connected between the primary coil 66 and the battery 34. The arm 86 is provided with a projection 88 adapted to be engaged by the cam 48 during the latter part of the rotation thereof, so that the circuit to the contacts 43 and 61 is broken after 60 the desired number of flashes have been effected but before the contact arm 42 stops vibrating. In effect, therefore, several blows are given the contacts 43 and 61 to flatten any peaks that might have been built up thereon because of 65 previous current flow.

In the event the flasher is to be utilized on a road sign, such as 71, which is remote and not susceptible to attention, or is unattended for long periods, I preferably include in the circuit 75

from the battery 34 a sun valve 91 of the character disclosed in my patent entitled "Sun valve", issued April 16, 1935, under Number 1,997,598. This valve is effective to open the circuit from 5 the battery 34 when the sun shines on the valve 91 and to establish the current flow when darkness arrives. Preferably, it is mounted on the top of the sign casing 71, as indicated in Figure 5, and affords an automatic control of the periods of operation of the flasher.

I claim:

1. A flasher comprising an electric flasher circuit, a pair of contacts controlling said circuit, a vibratile contact arm carrying one of said 15 contacts, a second vibratile contact arm carrying the other of said contacts, a periodically effective

timing means for imparting a succession of regularly recurring driving impulses to said contact arms, and an abutment for varying the initial point of flexure of one of said contact arms to vary the frequency of vibration of said contacts. 5

2. A flasher comprising an electric flasher circuit, a pair of contacts controlling said circuit, a vibratile contact arm carrying one of said contacts, a second vibratile contact arm carrying the other of said contacts, timing means for periodically imparting a driving impulse to one of said contact arms, and external means in the path of one of said contact arms for restricting to less than the natural amount the vibratile movement of said contact arm only. 10

EDWIN H. PENDLETON. 15
